GOLF CLUB HEAD

William R. Raymont, Palos Verdes Peninsula, Calif.
(25001 El Cortijo, Mission Viejo, Calif. 92675)

Filed Jan. 5, 1973, Ser. No. 321,369

Term of patent 14 years

Int. Cl. D21—02
U.S. Cl. D34—5 GH

FIG. 1 is a perspective view of a golf club head showing my new design. The portion is shown fragmentarily for convenience of illustration;

FIG. 2 is a side elevational view showing the ball-striking face;

FIG. 3 is a front end elevational view;

FIG. 4 is a top plan view;

FIG. 5 is a bottom plan view;

FIG. 6 is a rear end elevational view.

I claim:

The ornamental design for a golf club head, substantially as shown and described.
